ATTORNEY.

UNITED STATES PATENT OFFICE.

FREDERICK F. LANG, OF DETROIT, MICHIGAN.

RADIATOR-CORE.

1,394,311.

Specification of Letters Patent. Patented Oct. 18, 1921.

Application filed July 22, 1919. Serial No. 312,648.

To all whom it may concern:

Be it known that I, FREDERICK F. LANG, residing at Detroit, in the county of Wayne and State of Michigan, have invented new and useful Improvements in Radiator-Cores, of which the following is a specification.

This invention relates to radiators and has particular application to the construction of tubes therefor.

10 One of the principal objects of the invention resides in a provision of a tube which is corrugated to provide longitudinal air passages arranged exteriorly of the tube, and interior channels or grooves for the passage 15 of fine streams of water, thus producing a very efficient tube of this character.

In carrying out my invention, I preferably make the tubes spiral so that the fine columns of water and air will travel in spiral 20 form in their respective channels or passages.

Another object of the invention resides in the flattening of the opposite ends of the corrugated tube, thus increasing the strength 25 of the tube at these points, and providing for a rigid and durable connection between the tube and the headers of the radiator.

The nature and advantages of the invention will be better understood when the following detail description is taken in connection with the accompanying drawings, the invention residing in the construction, combination and arrangement of parts as 30 claimed.

35 In the drawing forming part of this specification like numerals of reference indicate similar parts in the several views and wherein:

Figure 1 is a fragmentary view of the 40 radiator embodying the tubes constructed in accordance with my invention.

Fig. 2 is a view in elevation of one of the tubes.

Fig. 3 is an end view.

45 Fig. 4 is a transverse sectional view taken on the line 4—4 of Fig. 2.

Referring to the drawing in detail, A indicates the spaced headers of the radiator, while C indicates the tube forming the subject matter of my invention.

Each tube is corrugated to provide a plurality of relatively small water channels 10 which are closely associated as shown in the

drawing. The longitudinal edges of each bead defined by the corrugations are brought together in contacting engagement, or they may be brought into close proximity to each other without contacting. However each bead provides a channel for the passage of a fine stream of water therethrough. The formation of the tube also provides air passages 11 extending longitudinally of and exteriorly of the tube, the passages 11 obviously being arranged between the respective beads defined by the corrugation. The tube is preferably spiral, so that the columns of water and air will follow a spiral course throughout the length of the tube thus assuring lowering of the temperature of the water to a proper degree before leaving the radiator. A tube constructed in the manner described is also susceptible of expansion and consequently will not break in cold weather.

The opposite ends of the tube are crimped as at 14, thus providing for reduced yet relatively thick extremities to provide for a rigid and durable connection between the tubes C and the respective heads of the radiator. It is quite frequent in radiator construction for the tubes to become broken or loosened at their point of connection with the radiator headers, when subjected to the vibration of the machine, but by the construction of the tube herein shown, the connection is materially strengthened by the increased thickness of material at the ends of the tube.

While I have shown and described what I consider the preferred embodiment of the invention, I desire to have it understood that I do not limit myself in this connection, and that such changes may be resorted to when desired as fall within the scope of what is claimed.

What I claim is:

A radiator tube corrugated to provide relatively small and closely associated water channels spirally arranged throughout the entire length of the tube, and air passages spirally arranged exteriorly of and between the water channels, the opposite ends of said tube being reduced to provide shoulders, and reduced extremities crimped with said channels flattened in overlapped relation.

In testimony whereof I affix my signature. 105
FREDERICK F. LANG.
